UNITED STATES PATENT OFFICE.

BERT J. NELSON, OF DETROIT, MICHIGAN, ASSIGNOR TO WHITE SHOWERS, INC., OF DETROIT, MICHIGAN, A CORPORATION OF MICHIGAN.

FLUID-PRESSURE OSCILLATING MOTOR.

Application filed January 26, 1925. Serial No. 4,973.

This invention relates to a fluid pressure oscillating motor, and is particularly designed for use in oscillating or turning a heavy section of a spray conduit used in an overhead irrigation system.

The particular problem encountered is the fact that this long section of the irrigation system is relatively heavy and it requires considerable force to oscillate the same.

With oscillating motors of the usual type it is necessary to build large size motors which are capable of developing sufficient power for turning the spray conduit or oscillating the same. It has generally been the practice to connect the spray conduits directly to the motor so that the fluid pressure operates directly against a piston which is so connected to the spray conduit that the same is oscillated once for each stroke of the piston.

In this invention it has been the object to reduce the size of the motor and to incorporate therein motion translating means whereby the motion developed by the motor can be applied in such a way as to give a large leverage for oscillating the spray conduit slowly. It has been found that the use of a small motor with this motion translating mechanism is sufficient to oscillate the heavy and long spray conduit of an overhead irrigation system.

Additional means are also provided for reversing the rocking motion of the motor at any number of predetermined points determined by the amount of ground area which it is desired to irrigate.

In the drawings:

Fig. 1 is an elevation of the motor constructed in accordance with my invention.

Fig. 2 is a plan view of the same.

Fig. 3 is a vertical section taken on the line 3—3 of Fig. 1.

Fig. 4 is a vertical section taken on the line 4—4 of Fig. 3.

Fig. 5 is a detail showing the connection between the pawl and reciprocating member and the means for reversing the rocking movement of the motor.

a designates a stationary feed pipe of a fluid pressure main which is suitably connected by the elbow *b* to the short length of pipe *c* which obviously, is also held stationary. This pipe section *c* supports, by a suitable swivel coupling *d*, the casting *e*, which is therefore allowed to freely turn

about the stationary pipe section *c*. A bracket *f* is clamped to the pipe section *c* and there is secured thereto a segmental rack *g* provided with a plurality of teeth *h*.

A short length of pipe *i* is screwed into the top of the casting *e* and supports the central casting *j* of the motor element. This casting *j* is provided with two chambers *k* and *m*, the latter chamber being in communication with the pipe section *i*, interior of the casting *e* and the feed pipe *a*, thereby placing the chamber *m* in communication with the source of fluid pressure. Secured to either side of this casting *j* are the cylinders *n* and *o*. Passageways are provided for connecting the chambers *k* and *m* with the interior of both cylinders, the passageways in each chamber positioned directly opposite each other, and arranged to be closed by the compound valves *p* and *q*. These valves are bridged at their free ends by the straps *r*, so that both valves are actuated together. In the position shown in Fig. 4, the valves are positioned to allow the incoming fluid pressure to enter the cylinder *n*, thereby forcing the piston *s*, which is not shown in Fig. 4 but is shown in Fig. 1, to the outer end and allowing the fluid pressure in the cylinder *o* to exhaust into the chamber *k* and out through the pipe *t* through the spraying nozzle *u*. Contained within the cylinder *o* is a piston *v* which is provided with the spring pressed striker *w* arranged to strike the strap *r*, carried by the valve, thereby causing the compound valves to both move to the right, as seen in Fig. 4, and reversing the valves whereby the fluid is allowed to flow into the chamber *o* from the chamber *m*, and exhaust the cylinder *n* into the chamber *k*. This will force the piston *v* to the left and bring the piston *s* into contact with the strap *r*, carried on the other end of the compound valves. This piston *s*, is provided with a similar striker *w*, as is the piston *v*, so that each piston actuates the valve when it reaches the bottom of its stroke for reversing the direction of the fluid, thereby reversing the motor.

The pistons are rigidly secured to a reciprocating frame *x*, so that both pistons are worked together. This reciprocating frame is provided with a pin *y* at an intermediate point and the casting *j* has pivoted thereto as at 1, a lever 2 which is slotted as at 3, the pin *y* being engaged in this slot,

so that as the reciprocating frame α moves, it carries with it the lever 2. Pivoted to this lever, as at 4, is a pawl 5. This pawl has pivoted thereto a downwardly extending leg 6 that is adapted to pass through a hole in the downwardly projecting arm 7, rigidly carried by the lever 2. A coil spring 8 is positioned about this leg 6, and is placed under compression and bears against the shoulders 9 on the leg 6 and the outwardly turned lip 10, carried by the arm 7. As shown in Fig. 5 this maintains the pawl in a certain set position. As shown in the drawings (see Fig. 1), the pawl is so positioned that the same may freely ride over the teeth of the rack when moved to the right, but on movement tending to move the pawl to the left the pawl engages the teeth and holds the pawl so that the movement must be compensated by a rocking movement of the motor element about its pivot. On the next return stroke of the piston the pawl slides over the next tooth of the rack and on the next power stroke of the piston the motor element is rocked a little further. This action is repeated until at a predetermined point it is desired to reverse the pawl so as to allow the reciprocating member which is connected to the pawl to operate the motor element in a reverse direction. This is obtained by a very simple device. A plurality of holes 11 are provided in the segmental rack γ , and the pins 12 may be fitted in these holes 11, one on each extreme end of the rack if it is so desired, to operate the motor the extreme limit of its movement. Obviously smaller degrees of movement may be obtained by inserting the pin into the intermediate holes. As shown in Fig. 5, this pin 12 is positioned in the path of the pawl 5, and as the same moves in the direction of the arrow the pawl engages the pin and is slowly forced backwardly until the pivot 13 between the leg 6 and the pawl passes the center line drawn through the pivot 4 and the outwardly extending lip or ear 10. The initial movement of this pawl will compress the spring 8, and as the same passes over the dead center the spring will then be allowed to expand and quickly throw the pawl over to the left, thereby providing a very snappy throw to the pawl. The motor develops a uniform reciprocating motion to the frame α and upon the reversing of the pawl the pawl grips the teeth of the rack in such a way as to reverse the rocking action of the motor.

With a device such as is shown in the drawings, the time interval for one complete movement of the pawl from one end of the rack to the other is about ten minutes, thereby providing a very slow oscillating movement of the motor, the relatively slow oscillating movement of the motor element being

translated from a relatively rapid reciprocating movement of the motor element.

Thus it will be seen that an intermittent oscillating movement is effected by a motor element which is relatively small, and this is accomplished by reason of considerable leverage through which the motor element acts. The invention is particularly directed to irrigating systems wherein relatively long lengths of pipe are oscillated, and inasmuch as relative movement is obtained between the rack device and the motor element, the rack device could be fixed to the oscillated pipe as well as to the stationary pipe, in which case the motor element would be fixed to the stationary pipe.

What I claim is:

1. A fluid pressure oscillating motor, comprising a support, a segmental rack secured thereto, a motor element pivoted to said support and including a piston and cylinder, means for conducting fluid under pressure to said motor element to reciprocate the piston, a reciprocating member secured to the piston and arranged to be reciprocated thereby, and intermittent motion translating means including a connection between the reciprocating member and rack for converting the relatively rapid reciprocating movement of the reciprocating member to a relatively slow oscillating movement of the motor element.

2. A fluid pressure oscillating motor, comprising a support, a segmental rack secured thereto, a motor element pivoted to said support and including a piston and cylinder, means for conducting fluid under pressure to said motor element for reciprocating the piston, a reciprocating member secured to the piston and arranged to be reciprocated thereby, motion translating means including a pawl and connections between the pawl and reciprocating member, whereby the pawl is so positioned as to engage the rack and cause the motor element to rock in one direction when the pawl is actuated by the reciprocating motion of the reciprocating member, and means for reversing the position of the pawl with respect to the rack for operating the motor element in a reverse direction.

3. A fluid pressure oscillating motor, comprising a support, a segmental rack secured thereto, a motor element pivoted to said support and including a piston and cylinder, means for conducting a fluid under pressure to said motor element to reciprocate the piston, a reciprocating member carried by the piston and arranged to be reciprocated thereby, motion translating means including a lever pivoted to said motor element, the free end of said lever being engaged by said reciprocating member and rocked thereby, a pawl carried by said lever and arranged to be moved when the lever is moved, said pawl arranged to engage with the rack and

positioned in such a manner as to cause the motor element to rock when the pawl is actuated by the reciprocating movement thereof, and means for reversing the position of the pawl for reversing the movement of the motor element.

4. A fluid pressure oscillating motor, comprising a support, a segmental rack carried thereby, a motor element pivoted to said support and including a piston and cylinder, means for conducting the fluid under pressure to said motor element to reciprocate the piston, a reciprocating member secured to the piston and reciprocated thereby, motion translating means for effecting a rocking movement of the motor between the reciprocating member and rack and including a pivoted pawl and connections between the said pawl and reciprocating member including resilient means for maintaining the pawl in a certain position for controlling the direction of the rocking movement of the motor element, pins removably secured to the rack which are projected in the path of the pawl for reversing the position of the pawl and causing the same to translate the reciprocating piston movement in a reverse oscillating or rocking movement of the motor element.

5. In a fluid pressure oscillating motor, the combination of a support, a segmental toothed rack carried by said support, a motor element pivoted to said support and provided with a pair of opposed cylinders and pistons, a reciprocating frame member secured to said pistons operating in said cylinders, a pawl connected with the reciprocating member arranged to engage the teeth of said segmental rack, means for introducing fluid under pressure alternately to said cylinders for actuating the reciprocating member and pawl connected therewith, whereby the pawl picks up a tooth on the rack at each complete stroke of the pistons thereby causing the said motor element to rock slowly in one direction, and means for reversing the pawl at a predetermined time to reverse said rocking action.

6. A fluid pressure motor, comprising in combination a pair of supports mounted for

movement relative to each other, a rack device secured to one support, a motor element consisting of a cylinder and a piston secured to the other support, means for conducting the fluid to the cylinder to reciprocate the piston, means operatively connected to the piston including a dog for engagement with the rack whereby a reciprocating movement of the piston is translated into an intermittent movement between the rack and the motor element, and means for reversing the direction of the intermittent movement as between the rack and the motor element.

7. A fluid pressure motor, comprising in combination a pair of supports mounted for relative movement, a rack device secured to one support, a motor element secured to the other support including a cylinder and a piston, means for conducting fluid to the cylinder for reciprocating the piston, a dog mounted on the motor element and operatively connected to the piston and engaging the rack device whereby reciprocating movement of the piston is translated into an intermittent movement between the motor element and the rack in one direction, and means on the rack and acting on the dog to reverse the direction of such intermittent movement.

8. A fluid pressure motor, comprising in combination a pair of supports mounted for relative movement, a rack device secured to one support, a motor element secured to the other support consisting of a cylinder and a piston, means for conducting fluid under pressure to reciprocate the piston, a pawl pivotally mounted on the motor element and engaging the rack, means operatively connecting the piston and the pawl whereby the pawl slides along the rack in one movement of the piston and locks to the rack in another movement of the piston to cause relative intermittent movement between the two supports, and means for swinging the pawl on its pivot to change its position to reverse the direction of said intermittent movements.

In testimony whereof I have affixed my signature.

BERT J. NELSON.
